UNITED STATES PATENT OFFICE

91,468

DESIGN FOR A STORE FRONT

Daniel J. O'Connell, Norman J. Schlossman,
John Demuth, and Jerrold Loeb, Chicago, Ill.,
assignors to O'Connell's Inc., Chicago, Ill.

Application November 17, 1933. Serial No. 49,783

Term of patent 14 years

To all whom it may concern:

Be it known that we, DANIEL J. O'CONNELL, NORMAN J. SCHLOSSMAN, JOHN DEMUTH, and JERROLD LOEBL, all citizens of the United States, residing at Chicago, in the county of Cook and State of Illinois, have invented a new, original, and ornamental Design for Store Fronts, of which the following is a specification, reference being had to the accompanying drawing forming a part thereof wherein:

We claim:

The ornamental design for a store front substantially as shown.

DANIEL J. O'CONNELL.
NORMAN J. SCHLOSSMAN.
JOHN DEMUTH.
JERROLD LOEBL.
